RECEPTACLE

Richard C. Talbot, Durham, N. C., assignor to
 Wright's Automatic Tobacco Packing Machine
 Company, Durham, N. C., a corporation of
 North Carolina

Application May 2, 1940, Serial No. 333,016

8 Claims.

(Cl. 229—14)

The present invention relates to improvements in receptacles, and more especially to those suitable for use in the packing of food and other products.

One of the primary objects of the invention is to provide a receptacle comprising an outer carton or similar container and an inner liner composed of a material which is impervious to air and moisture and is effectively sealed to form an air and moisture proof compartment whereby the products enclosed in the inner liner are protected and preserved in their original condition, products, for example like cereals or breakfast food which are dry, being preserved in that condition by protecting them from moisture in the atmosphere, products, for example like coffee, tea or tobacco, which are moist or damp or subject to loss or deterioration, being preserved in their original condition by sealing them within the inner liner, and products containing constituents capable of penetrating an ordinary paper carton and soiling it or of contaminating it being confined by the inner liner which is impervious to such constituents and therefore confines them therein, the products in any case being protected from loss or deterioration and from contamination from the atmosphere or other exterior influences.

A more particular object of the invention is to provide an inner liner of this character which is adapted for use in a carton of conventional type, thus enabling the receptacles to be filled with the same facility as ordinary cartons, as by the usual types of carton filling machines, and the filled receptacles being suitable for packing, shipping, storing and handling like ordinary cartons.

Another object is to provide an improved closure for the inner liner which can be readily inserted and sealed therein to provide an effectively sealed compartment for the contents of the receptacle.

A further object of the invention is to provide an inexpensive receptacle of this character having an inner liner which is divided into a plurality of compartments by insertion and sealing of a plurality of closures therein whereby a closure forming the bottom of one compartment will form an air and moisture proof closure for the top of the compartment beneath it, this multiple compartment form of receptacle being especially suitable for the packing of different kinds of products in the different compartments, or the packing of relatively small quantities of the same product in the different compartments and from which the product may be removed successively.

as used, the compartments being opened one at a time by the consumer so that the rest of the compartments remain sealed against air and moisture and thus maintaining the products therein in a fresh condition until used.

The preferred embodiments of the invention are shown in the accompanying drawing and will be herein described in detail, but it is to be understood that the invention is not restricted to the precise details shown as equivalent constructions are contemplated and are to be included within the scope of the claims.

In the drawing:

Figure 1 is a perspective view of a receptacle embodying the present invention;

Figure 2 is a vertical section taken longitudinally through the receptacle as provided with a single compartment, the end closing flaps of the outer carton being unfolded;

Figure 3 is a view similar to Fig. 2 but showing the receptacle as provided with a plurality of compartments;

Figure 4 is a side elevation of the inner liner after it has been formed but before its insertion into the carton;

Figure 5 is an edge view of the inner liner as viewed from the right in Fig. 4;

Figure 6 is a perspective view on an enlarged scale, of the liner, illustrating the manner of folding one of its bottom corners;

Figure 7 is a perspective view of one of the closure members for the inner liner; and

Figure 8 is a detail perspective view of one of the corners of the closure member, illustrating the manner of folding it.

Similar parts are designated by the same reference characters in the several figures.

The improved receptacle, as shown in the present instance, comprises an outer carton 1, an inner liner 2 and one or more closure members 3.

The outer carton 1 is preferably of a conventional type formed from heavy paper or cardboard into rectangular form and provided at the ends with flaps 4 and 5 which are foldable inwardly and upon one another to close the ends of the carton, these flaps being secured in closed condition in any suitable or well known way as, for example, by adhesives.

The inner liner 2 provided by the present invention is composed of any suitable relatively thin and flexible sheet material which is impervious to air and moisture, but it is preferably composed of waxed paper, "Cellophane" of the waterproof variety or similar material which is transparent or semi-transparent and has a wax-

like coating which is suitable for heat sealing, or transparent sheet rubber such as that known as "Pliofilm" which is vulcanizable by heat and pressure and thus heat sealable. This liner is preferably formed into rectangular shape from a rectangular sheet of the material of suitable dimensions by folding the sheet to bring its ends into positions to form a pair of parallel opposed sides 6 and 7 connected at their lower ends by the intermediate portion of the sheet which forms a seamless bottom 8, and by folding the longitudinal edges of the sheet toward one another and into overlapping relation to form the edge walls 9 and 10 and the connecting seams 11 and 12. The junctions of lower ends of the side and edge walls of the liner form overlapping triangular folds 13 and 14. The edge seams 11 and 12 and the triangular corner folds 13 and 14 may be united to seal the lower corners of the liner by adhesive, but they are preferably heat sealed by applying heat and pressure, which may be readily accomplished with the aid of a mandrel placed within the liner, after which the completed liner may be placed within the carton in which it fits closely, or the liner may be inserted into the carton before its longitudinal seams and corner folds are secured, after which said seams and corner folds may be united by adhesive or heat sealing which will secure the inner liner in place in the carton, with the ends of the liner positioned at the lines of fold of the carton closing flaps so that the liner occupies the body portion of the carton.

The closure members 3 are each composed preferably of the same kind of material as that composing the inner liner. Each closure member is also preferably formed from a rectangular sheet of the material into a rectangular tray-like structure the side and end edges 15 and 16 of which are turned up at right angles to the rest of the sheet, these edges thus forming a surrounding flange, the corners of the flanges where the side edges meet the end edges being formed into triangular folds 17 the overlapping portions of which may be united by adhesive but are preferably heat sealed by applying heat and pressure to these corner folds. Each flanged closure member is of a size to closely fit into the inner liner with its surrounding flange in close contact with the enclosing walls of the liner.

In using the improved receptacle, the inner liner 2 is inserted into an end of the carton, and the end of the carton adjacent to the bottom 8 of the liner may be closed by folding and suitably securing its closing flaps, the top of the carton and of the inner liner being open for filling. The product to be packed in the receptacle may be introduced into the inner liner in any suitable manner, the receptacle being especially adapted for filling by any suitable filling machine.

If the receptacle is to be filled with a single body of material, a single closure member 3 is inserted into the upper end of the inner liner so that its surrounding flange projects upwardly from the closure, and the latter is sealed in the inner liner by uniting its surrounding flange to the enclosing wall of the liner by adhesive or preferably by heat sealing by the application of heat and pressure, the surrounding and exposed flange of the closure enabling an anvil or mandrel to be inserted therein to receive and sustain the inward pressure applied, whether the closure is sealed within the inner liner by adhesive or by heat sealing. After filling and sealing in the

closure member, the closing flaps at the adjacent end of the carton are folded and suitably secured in closed condition and the package is then completed.

If the receptacle is to be filled with a plurality of bodies or distinct quantities of material of either the same kind or of different kinds, a quantity of the material amounting to a desired part or fraction of the total contents of the completely filled receptacle is first introduced into the lower part of the inner liner, after which a closure member 3 is introduced into the inner liner on top of the material and sealed therein by its surrounding flange, and other fractional quantities of material and closure members are successively introduced into the inner liner and sealed therein until the receptacle is filled, after which the closing flaps of the carton are folded and suitably secured in closed condition. In employing such a fractional or multiple filling method, each part of the contents of the receptacle will be not only separate and distinct from the other parts thereof, but will be sealed in an air and moistureproof compartment, each closure member sealing the bottom of one compartment and the top of the compartment beneath it. Consequently, if the consumer desires to use only a part at a time of the total contents of the package, the material or product contained in each compartment may be removed, as by puncturing or removing the closure member immediately overlying it, the rest of the closure members however remaining intact so that the product or material contained in the rest of the separate compartments remain sealed from exterior air and moisture so that these portions of the product or material will be preserved in their original or fresh condition.

By sealing the air and moistureproof closure member or members to the surrounding walls of the air and moistureproof inner liner, effective sealing of the compartment or compartments within the liner is provided, the formation of the closure member or members as described enabling such sealing to be accomplished with facility and certainty. As the inner air and moistureproof liner extends throughout the length of the carton, it provides a complete seal for the entire contents of the receptacle and it protects the carton from soiling by fluid constituents of the products when such products are contained therein, as such constituents are intercepted by the inner liner.

Although both the liner and the closure member or members are preferably composed of a heat sealable material, it will be understood that either the liner alone or the closure member or members may be composed of heat sealable material. Moreover, although in using a plurality of closure members, these members have been described as being sealed individually and in succession as the different portions of the total contents of the receptacle are introduced, it will be understood that the multiple closure members may be sealed simultaneously, after the receptacle has been completely filled, by applying pressure or heat and pressure to the exterior of the carton, the inward pressure so applied being sustained by the partition-like formation of the closure members to which the pressure would be applied edgewise and which would be supported against deformation by the material filling the compartments.

I claim as my invention:

1. A receptacle comprising a carton having a

body and transversely foldable top closing flaps, an inner liner therein composed of air and moistureproof material closed and sealed at its lower end and terminating at its upper end in the plane of the fold lines of said flaps, and a closure member composed of air and moistureproof material inserted into the upper end of the liner and having its surrounding edge sealed to the inside surfaces of the enclosing walls of the liner, said closing flaps being foldable directly onto said closure member.

2. A receptacle comprising a carton having a rectangular body and inwardly foldable closing flaps at its upper end, an inner liner inserted therein and coextensive with the full length of the body thereof, said liner being composed of an air and moistureproof material and closed and sealed at its lower end and terminating at its upper end in the plane of the fold lines of said flaps, and a closure member composed of an air and moistureproof material inserted into the upper end of the liner and having a surrounding flange sealed to the inner surfaces of the enclosing walls of the liner immediately adjacent to the plane of the fold lines of said flaps.

3. A receptacle comprising a carton having transversely foldable closing flaps at the top thereof, an inner liner therein composed of air and moistureproof material closed and sealed at its lower end and terminating at its upper end in the plane of the fold lines of said flaps, and a closure member composed of air and moistureproof material inserted into the upper end of the liner and having its surrounding edge heat sealed to the inside surfaces of the enclosing walls of the liner immediately adjacent to the plane of the fold lines of said closing flaps.

4. A receptacle comprising a carton having transversely foldable closing flaps at the top thereof, an inner liner inserted therein and extending the full length of the body thereof, said liner being composed of an air and moistureproof heat sealable material and closed and heat sealed at its lower end and terminating at its upper end in the plane of the fold lines of said flaps, and a closure member composed of an air and moistureproof heat sealable material inserted into the upper end of the liner and having a surrounding flange heat sealed to the inner surfaces of the enclosing walls of the liner immediately adjacent to the plane of the fold lines of said flaps.

5. A receptacle comprising a carton having transversely foldable top closing flaps, an inner liner therein composed of an air and moistureproof material and having a folded bottom closure and terminating at its upper end in the plane of the fold lines of said flaps, and a plurality of members sealed within said liner at intervals in its length, one of said members closing the upper end of the liner and the other members dividing the liner into a plurality of separate sealed compartments.

6. A receptacle comprising a carton having transversely foldable top closing flaps, an inner liner therein composed of an air and moistureproof material and having a folded bottom closure and terminating at its upper end in the plane of the fold lines of said flaps, and a plurality of members heat sealed within said liner at intervals in its length, one of said members being sealed to the liner immediately adjacent to its upper end and the other members dividing the liner into a plurality of separate sealed compartments.

7. A receptacle comprising a carton having transversely foldable top closing flaps, an inner liner therein composed of an air and moistureproof material and having a folded and heat sealed bottom closure and terminating at its upper end in the plane of the fold lines of said flaps, and a plurality of partition like members located at intervals within the liner and having surrounding flanges lying flatwise against and heat sealed to the inner surfaces of the surrounding walls of the liner, one of said members being sealed to the liner immediately adjacent to the fold lines of said flaps and the other members dividing the liner into a plurality of separate sealed compartments.

8. A receptacle comprising a carton having top closing flaps foldable inwardly on transverse lines at its upper end, an inner liner therein composed of air and moistureproof heat sealable material closed and heat sealed at its lower end and terminating at its upper end in the plane of the fold lines of said flaps, and a closure member composed of air and moistureproof heat sealable material inserted into the upper end of the liner and having its surrounding edge heat sealed to the inside surfaces of the enclosing walls of the liner immediately adjacent to the plane of the fold lines of said flaps.
